UNITED STATES PATENT OFFICE.

THOMAS A. DICKS, OF PITTSBURGH, PENNSYLVANIA, ASSIGNOR TO STANDARD STEEL PROPELLER COMPANY, OF PITTSBURGH, PENNSYLVANIA.

CONTROL MECHANISM FOR PROPELLERS.

Application filed June 30, 1921. Serial No. 481,600.

To all whom it may concern:

Be it known that I, THOMAS A. DICKS, a subject of Great Britain, and resident of Pittsburgh, in the county of Allegheny and State of Pennsylvania, have invented certain new and useful Improvements in Control Mechanism for Propellers; and I do hereby declare the following to be a full, clear, and exact description of the invention, such as will enable others skilled in the art to which it appertains to make and use the same.

This invention relates to improvements in control mechanism for propellers, and more particularly to means for adjusting and reversing the angle of propeller blades while in motion,—one object of the invention being to provide simple and efficient means whereby quick action in the adjusting or shifting of the propeller blades shall be secured.

A further object is to provide mechanism for the purpose stated, which shall be positive in operation, comprise a minimum number of parts, and which shall be reliable in the performance of its functions.

A further object is to so construct control mechanism for angling and reversing propeller blades, that the driving power of the propeller shall be simultaneously regulated as to speed and power in accordance with the changing angularity or adjustment of the blades from one position to another, as occasion may require during the maneuvering of the machine.

A further object is to so construct control mechanism of the adjustable blades of an aeroplane or hydroplane propeller, that the angularity of the blades may be easily and accurately adjusted to give the best results during the starting of the flight of the machine; so that the angle of the blades may be readily increased and the efficiency of the engine increased when the machine is in flight; so that the angle of the blades may be quickly brought to "neutral" position when the machine is to make a landing and then reversed so that the propeller will act as a brake

against the air and permit the machine to effect a landing in a minimum amount of space.

A further object is to so construct propeller control mechanism that the angularity of the propeller blades and the control of the engine shall be under the simultaneous control of the operator and so that he may be enabled to start or stop the engine independently of the automatic control.

A further object is to so construct and arrange control mechanism for the reversible blades of the propeller of an aeroplane or similar machine, that the same can be handled with one hand and without interfering with other movements of the operator in handling the machine.

With these and other objects in view, the invention consists in certain novel features of construction and combinations of parts as hereinafter set forth and pointed out in the claims.

In the accompanying drawings; Figure 1 is a plan view of mechanism embodying my improvements and showing the application of the same to an aeroplane; Figure 2 is a side elevation; Figure 3 is an enlarged detail view showing the latch devices for the carburetor control rod; Figures 4, 5 and 6 are views, (Figures 4 and 5 being taken at right angles to each other) and showing parts of the mechanism which is connected with the propeller blades for adjusting them and Figures 7, 8, 9 and 10 are views showing the details of the hand lever and handle constructions.

In the drawings, I have shown at 1, the front portion of the crank-case of an engine mounted in the fuselage of an aeroplane, the operator's seat in the latter being shown at 2. The projecting portion of the engine shaft 2^a enters and is keyed to the tubular hub 4 of a propeller and the forward end of said shaft may be threaded to receive a nut 5. The tubular hub may be interiorly threaded near its outer end to receive a sleeve nut 6 which bears against the nut 5 in a manner to serve to lock the latter. The propeller hub is provided with arms 7 on which the inner end portions of hollow metal blades

7^a are suitably mounted to turn so that they may be angled or their angularity reversed. The circular inner end portions of the blades may be provided with bands 8, each of 5 which is provided with a perforated lug 9,—the lug on one blade-band being disposed in a position diametrically opposite the lug on the other blade-band. These perforated lugs receive pins 10 which project laterally 10 from members 11 mounted to slide longitudinally on the outside of the hub, so that when said slide members are moved, rotary motion will be imparted to the propeller blades for adjusting their angularity. The 15 slide members 11 are carried by a sleeve 12 mounted on the propeller hub 4, and said sleeve is rotatively connected, through the medium of suitable anti-friction devices, with a control ring 13,—the latter being 20 provided with diametrically opposite angular enlargements 14, and from the latter, pintles 15 project.

A bracket 16 is securely fastened to the crank-case of the engine and is provided 25 with pairs of guides 17 to receive the angular enlargements 14 on the central ring 13 to guide the movements of the latter and prevent the same from turning. The bracket 16 is provided with a laterally projecting 30 tubular member 16^a and the latter is supported at its outer end by a bracket 18 secured to the frame-work of the machine. A shaft 19 is mounted in the bracket 16 and its tubular lateral extension 16^a and 35 said shaft has secured thereto, a forked or yoke-lever 20,—the free ends of the latter being formed with perforated bosses 21 located diametrically opposite each other to receive the pivot pins of links 22 and these 40 links are provided at their rear ends with suitable openings to receive the pintles 15 on the control ring 13. The yoke-lever 20 is thus connected with the control ring 13, so that when the shaft 19 is turned, the 45 control ring will be moved in such manner as to slide the arms or members 11 and impart movement as above explained to the blades for turning them.

A lever 22^a (of the walking beam type) 50 is secured centrally between its ends to the projecting end of the shaft 19, and a similar lever or walking beam 23 is secured to the outer end of a shaft 24, the latter being mounted in a suitable bearing in a 55 bracket 25 secured to the framework of the machine near the cockpit thereof. The upper arms of the respective levers or walking beams 22^a and 23 are connected by a rod or pitman 26 and their lower arms are 60 connected by a similar rod or pitman 26^a.

The hub portion at the lower end of a control lever 27 is mounted on a stud 28 projecting from the bracket 25 and carries a pinion 29 to mesh with a toothed segment 65 30 secured to the shaft 24,—the purpose of

said control lever being to provide manually operable means located within convenient reach of the operator whereby he may readily operate the mechanism above described for angling the propeller blades, for reversing the angularity of the same or for bringing the same to neutral positions.

A slide 31 is suitably mounted on the control lever and has mounted therein, a worm 32 to mesh with a worm rack 33 secured to the bracket 25. The slide 31 is connected by a link 34, with one arm of a bell-crank 35 pivotally mounted on the control lever 27,—said bell-crank being so normally disposed that its pivotal mounting 70 will be on a dead center with relation to the pivotal connections of the link 34 with said bell-crank and with the slide, whereby the worm 32 will be locked against movement in a direction away from the segmental rack 33. To the other arm of the bell-crank 35, one end of a rod or link 36 is pivoted and the other end of said rod or link is pivoted to an arm 37. A tubular handle 38 is connected with the control lever 27 through the medium of a handle-bail 38^a in which said handle is revolvably mounted. The arm 37 above referred to is secured to a socketed nut 39 revolvably mounted in the tubular handle 38 and having therein spiral 80 ribs 40 which cooperate with spiral grooves 41 in a plunger 42 located within the handle 38. The plunger 42 is provided at one end with a head 43 having an angular socket 44 to receive a similarly shaped stud 45 carried by a plate 46 attached to the bail 38^a, to prevent said plunger from turning. The plunger is retained in and returned to its normal position relatively to the socketed nut 39 by means of a spring 46^a which encircles said plunger and bears at one end against a collar 47 secured thereto,—the other end of said spring bearing against a collar 48 which loosely encircles the plunger and bears against a shoulder 49 in the handle 38. A finger lever 50 is pivoted to an arm 51 projecting from the handle and provided with an arm 52 which engages in a groove 53 in the plunger head.

When the operator grasps the handle 38 of lever 27 and presses the finger lever 50, the plunger 42 will be withdrawn against the resistance of the spring 46 and the socketed nut 39 will be turned, thus moving the arm 37 and transmitting motion, through the rod or link 36 to the bell-crank 35 to move the latter and break the dead center lock which holds the slide 31 and move the latter in a direction to withdraw the worm 32 from the worm segment 33. The operator may now move the lever 27 to operate the propeller blade adjusting mechanism. When the finger lever 50 shall have been released, the spring 46 will operate to cause the slide 31 to move toward the segment 33 and the

worm 32 to again mesh with the latter, such movement of the slide being assisted by the action of a spring 54 attached at one end to said slide and connected at its other end with the lever 27,—and the lever 27 may thus be locked in any position to which it may be moved to hold the blades of the propeller at any desired adjustment.

In order to provide means for effecting slight adjustments of angularity of the propeller blades and for operating the control lever 27 when the pressure is too great on the mechanism to permit said lever to be operated with the use of the handle 38, the devices now to be described may be employed: The shaft of the worm 32 is extended beyond one of its bearings and has secured thereto, a bevel pinion 55. The shaft of a hand wheel 56 is mounted in a suitable bearing on the slide 31 and carries a bevel pinion 57 meshing with the bevel pinion 55. It is apparent that by turning the hand wheel 56, motion will be imparted to the worm 32 and the meshing of the latter with the worm rack 33 will cause movement of the control lever to effect blade adjustment as above explained.

In the control of the angling and reversing of the blades of an aeroplane propeller, the speed and power of the driving engine to meet varying conditions resulting from the adjustments of the propeller blades, are important factors. If the blade angle be lessened, decreased driving power will be required and unless the gas mixture be reduced, the engine will speed up. When the blades are moved to neutral positions, in changing the angularity to reverse the action of the propeller, the gas mixture must be cut off as the blades pass the neutral positions; otherwise the engine will race to a very high speed and possibly result in damage thereto and to the propeller, and when the blades reach the reverse angularity, the gas mixture must be turned on again to the right amount to keep the propeller at the proper speed. To meet the conditions above outlined, my improved propeller control mechanism includes means for controlling operation of the engine simultaneously with the adjusting of the propeller blades, and with the use of a single control lever 27. These means will now be explained in detail.

A cam plate 58 is fitted on the hub portion of the control lever 27 and is provided with an arm 59 lying parallel with a portion of the control lever,—said arm being provided with a transverse slot 60 for the accommodation of a bolt 61 whereby the cam plate may be adjustably secured in position. The plate 58 is provided with a cam-way 62, with which a roller 63 carried by a two-part arm 64 cooperates. The arm 64 constitutes one member of an approxi-

mately L-shaped lever 65 pivotally mounted on the bracket 25 at 66. The upper end of the lever 65 is connected, by means of a rod 67 with the upper end of a link 68, the lower end of the latter being pivotally supported by a small bracket 69 secured to the framework of the fuselage. The pivot pin 70 which connects the rod 67 with the link 68, projects laterally and enters a slot 71 in a bar 72 which forms part of a rod 73 leading to and connected with the carburetor control (not shown). A plate or lever 74 is pivotally mounted on the bar portion 72 of the rod 73, and to this plate, a latch 75 is pivoted, the hooked end of the latter being pressed (by a spring 76 bearing against a toe 77 on said latch and against a part 78 of the bar 72) to position to engage the pivot pin 70 and retain the same normally at one end of the slot 71 in the part 72. The pivoted plate or lever 74 is also provided with a toe 79 to bear against the toe 77.

From the construction and arrangement of parts above described, it will readily be seen that when the control lever 27 is operated to effect adjustment of the propeller blades, the cam plate 58 will also be moved and operation of the carburetor control will be effected in accordance with the shape of the cam-way 62,—the latter being so shaped as to cause operation of the carburetor control in a manner to control the operation of the engine during different adjustments of the propeller blades, as previously mentioned.

In order that the operator may be enabled to control the carburetor independently of the automatic control above described, for the purpose of starting or stopping the engine, a hand lever 80 is provided. This lever is located within convenient reach of the operator, and it is connected by a rod 81, with the pivoted plate or lever 74. By moving the hand lever 80 rearwardly motion will be imparted, through the rod 81 to the pivoted plate or lever 74, first to release the latch from the pin 70 to disconnect the automatic control rod and then to move said rod to effect operation of the carburetor control.

Various changes might be made in the details of construction of my invention without departing from the spirit thereof or limiting its scope, and hence I do not wish to restrict myself to the precise details herein set forth.

Having fully described my invention what I claim as new and desire to secure by Letters-Patent, is:—

1. In control mechanism for propellers, the combination with a propeller having adjustable blades, and adjusting means connected with said blades, of a shaft, a forked lever secured to said shaft and connected

with said adjusting means, a walking beam lever secured to said shaft, a control lever, a second walking beam lever, gearing between said last-mentioned lever and said control lever, and rods connecting the respective walking beam levers.

2. In control mechanism for propellers, the combination with a propeller having adjustable blades, and adjusting means connected with said blades, of a bracket having parallel guide arms for guiding said adjusting means, said bracket having a lateral tubular extension, a shaft mounted in said bracket and its tubular extension, a forked lever secured to said shaft and connected with said adjusting means, a second lever secured to said shaft, a control lever, connection between said control lever and said second lever, and means for locking and 20 for releasing said control lever.

3. In control mechanism for propellers, the combination with a propeller having adjustable blades, and adjusting means for said blades, of a control lever, connections between said control lever and the blade adjusting means, an engine control member having a slotted part, a cam operable by the control lever, a lever having an arm cooperable with said cam, a pivoted link, a rod 30 pivoted at one end to said last mentioned lever, a pin pivoting the other end of said rod with said link, said pin entering the slotted part of the engine control member, a latch normally engaging said hand pin, a hand 35 lever, and means connecting said lever with said latch, whereby movement of said hand lever will release the latch from said pin and then move the engine control member.

4. In control mechanism for propellers, the combination with a propeller having adjustable blades, adjusting means for said blades, and an engine control member, of a control lever, connections between said control lever and said blade adjusting means, 45 means operable by the control lever for simultaneously operating said engine control member, a manually operable lever, and means operable by said last-mentioned lever to disconnect the simultaneously operable means from the engine control member 50 and move said member to control the starting or stopping of the engine.

5. In control mechanism for propellers, the combination with a propeller having adjustable blades, and means for adjusting said blades, of a control lever, connections between said control lever and the blade adjusting means, a segment having worm teeth, a slide on said lever, a worm mounted 60 in said slide, and means for moving said slide to move the worm out of and into mesh with the worm teeth of said segment.

6. In a control mechanism for propellers, the combination with a propeller having adjustable blades, and means for adjusting

said blades, of a control lever, connection between said control lever and the blade adjusting means, a segment having worm teeth, a worm mounted in said lever and adapted to mesh with the worm teeth of the segment, a hand wheel, and gearing between 70 said hand wheel and said worm.

7. In control mechanism for propellers, the combination with a propeller having adjustable blades, and adjusting means for said blades, of a control lever, connections between said control lever and the blade adjusting means, a segment having worm teeth, a slide mounted on the control lever, a worm carried by said slide and adapted to mesh with worm teeth of said segment, means carried by said lever to operate the slide to move the worm out of and into mesh with the worm teeth of said segment, a hand wheel carried by said slide, a pinion carried 80 by said worm, and a pinion operable by said hand wheel and meshing with the first-mentioned pinion.

8. In control mechanism for propellers, the combination with a propeller having adjustable blades, and adjusting means for said blades, of a control lever connections between said lever and the blade adjusting means, a toothed segment, a slide mounted on the control lever, an engaging member carried by said slide for cooperation with the toothed segment, a bell-crank on said lever, a link connecting one arm of said bell-crank with said slide whereby a dead-center-lock 90 may be formed from said slide and engaging member, and means carried by the control lever and connected with the other arm of the bell-crank for moving said slide and engaging member.

9. In control mechanism for propellers, the combination with a propeller having adjustable blades, and adjusting means for said blades, of a control lever, connections between said lever and the blade adjusting means, a toothed segment, a slide carried by the lever, an engaging member carried by said slide for cooperation with said toothed segment, a bell-crank mounted on said lever, a link connecting one arm of said bell-crank with said slide, a handle on said lever, an arm carried by said handle, a connection between said arm and the other arm of the bell-crank, and means carried by the handle for operating the arm thereon.

10. In control mechanism for propellers, the combination with a propeller having adjustable blades, and adjusting means for said blades, of a control lever, connections between said control lever and the blade adjusting means, a toothed segment, an engaging member mounted on the lever for cooperation with said toothed segment, a tubular handle on said lever, a socketed nut mounted in said handle and having internal spiral ribs, a plunger mounted in said handle to enter said

socket nut and having spiral grooves to receive said ribs, a spring tending to move said plunger in one direction, means for preventing said plunger from turning, manually operable means for moving said plunger in one direction, an arm secured to the socketed nut, and means connecting said arm with said engaging member.

In testimony whereof I have signed this specification in the presence of two subscribing witnesses.

THOMAS A. DICKS.
